TIE HOLDER

Julius Mayer, Fort Lauderdale, Fla.

Application January 16, 1956, Serial No. 559,362

2 Claims. (Cl. 24—49)

This invention relates to a tie clasp and has particular reference to a novel form of tie clasp whereby the outer or exposed end of the tie is securely anchored with respect to the tail end of the tie and the shirt front and avoids the usual and well known overlapping tie clasps that serve to jointly hold both the front and rear sections of the tie simultaneously with respect to the shirt front of the wearer.

The invention embodies a novel preferably metallic tie clasp for use in connection with a tie, the exposed side of which is provided with a reinforced opening through which is passed a stud that has interlocking engagement with a clasp and with the clasp serving to securely hold the tail portion of the tie with respect to the shirt front.

It is contemplated of course that the necktie is particularly adapted for the novel clip hereinafter to be disclosed, although the necktie having the preformed aperture may either be furnished in combination with the clasp or any tie may be subsequently apertured and reinforced whereby it accommodates itself to the clip of this invention.

Novel features of construction and operation of the device will be more clearly apparent during the course of the following description, reference being had to the accompanying drawings wherein has been illustrated the preferred form of the device and wherein like characters of reference are employed to denote like parts throughout the several figures.

In the drawings:

Figure 1 is a front elevation of a necktie in tied position and with the clasp being illustrated in dotted lines and in use.

Figure 2 is a perspective view of the clasp taken from the rear side thereof.

Figure 3 is a perspective view of the clasp and an associated hold-down button taken from the front side of the device.

Figure 4 is a top edge view of the clip and associated hold-down button.

Figure 5 is an enlarged longitudinal section taken substantially on line 5—5 of Figure 1, and

Figure 6 is a fragmentary front elevation of a necktie showing a reinforced stud receiving slot therein.

Referring specifically to the drawings the necktie 5 is of conventional construction having a front display portion 6 and an underlying tail portion 7. The necktie is used in a conventional manner with a shirt 8. At a selected position intermediate the width of the portion 6 of the tie, there has been formed a square aperture 9 entirely through the portion 6 and with the marginal edges of the slot preferably being reinforced similar to a buttonhole. A hold-down button or stud 10 having a shank portion 11 is adapted to be passed through the slot 9 in use and whereby to hold the portion 6 of the tie against flopping or otherwise shifting. The head portion of the stud 10 may be ornamented in any desirable man-

2

ner or may contain precious or semi-precious stones. The shank portion 11 is preferably square in shape, and is provided with a transverse aperture 12, for a purpose to be presently described.

5 The clasp, here indicated by the numeral 13, is preferably formed of sheet metal or the like having a predetermined flexibility. The clasp may be formed of any desirable metal or possibly plastic. The clasp 13 embodies a sheet of metal bent upon itself to form a rectangular front wall 14 and a parallel spaced tongue 15. The tongue 15 is preferably of a reduced transverse width and serves as that portion of the clasp that engages behind the usual overlap of the shirt front. Formed substantially intermediate the length of the wall 14 and substantially intermediate its height, is a square aperture 16 extending entirely therethrough and with the aperture being dimensioned to receive the shank 11 of the button 10. Overlying the aperture 16 and extending from the rear side of the wall 14 is a socket forming housing 17. The housing 17 is transversely apertured as at 18 and with the aperture being in direct axial alignment with the aperture 12 of the shank 11 when the shank is in fully engaged relative to the housing. Soldered or otherwise connected to the rear face of the wall portion 14 is a tubular sleeve 19 and with the sleeve being internally threaded for the reception of a threaded pin 20 having a preferably knurled head 21. The bore of the sleeve 19 is in direct axial alignment with the aperture 18 of the housing 17 and with aperture 12 of the shank 11 when the shank is in fully seated relation. The leading end of the pin 20 is preferably formed smooth and with its terminal end rounded to facilitate its passage through the aperture 12 of the shank 11. While the pin 20 has been shown as being threaded, it will be apparent that the pin may be shifted through a suitable slide having frictional engagement for holding the pin in adjusted locking position.

30 In the use of the device, the necktie 5 is formed in the usual manner with the tail portion 7 fully covered by the exposed portion 6. The clasp 13 is then engaged with the tail portion 7 and the overlapping shirt front and shifted vertically to its approximate position where the aperture 16 will be in substantial alignment with the aperture 9 of the tie. As clearly shown in Figure 5, the tail portion 7 and an overlapping portion of the shirt front 8 is held in tensioned engagement with the projecting housing 17, thus securely holding the tail portion 7 and the shirt front in clipped assembly with the clip 13. The operator then engages the shank 11 of the button 10 through the aperture 9 and into the aperture 16 for a fully seated engagement within the housing 17, in which position the several apertures 12 and 18 are in alignment. The pin 20 is then turned inwardly by the head 21, causing its leading tail portion to pass through the apertures 18 and 12, securely anchoring the button 10 against accidental displacement. In this position the exposed portion 6 of the tie is held in definite relation to the shirt front against shifting. When the tie is to be removed, the pin 20 is turned in a reverse direction causing its terminal end to disengage the shank 11 and the housing 17, after which the stud 10 may be easily removed, freeing the portion 6 of the tie after which the clip may be disengaged from the shirt and the tail portion 7. While the sleeve 19 has been shown as being shorter than the length of the pin, the sleeve 19 and the housing 17 may be formed as an integral unit and connected to the rear side of the wall 14.

35 40 45 50 55 60 65 70 It will be apparent from the foregoing that a very novel form of tie clasp has been provided. The clasp is easily connected and adjusted vertically by sliding motion along the tail portion 7 and the shirt front whereby to quickly and easily align the aperture 16 with the aperture 9 of the

tie. The parts in their assembled relation as shown in Figure 5 securely anchors the tie in the desired position and through the medium of this anchor, the entire clasp mechanism is held against loss. The device is cheap to manufacture, simple in construction, is strong, durable and highly effective in use.

It is to be understood that the invention is not limited to the precise arrangement shown but that changes are contemplated as readily fall within the spirit of the invention as shall be determined by the scope of the subjoined claims.

Having described my invention, what I claim as new and desire to secure by Letters Patent is:

1. A clip for use with a necktie having an aperture formed therein, the clip being of U-shape and having a flat front wall and a parallel and flexible tongue, the front wall intermediate its length being provided with a forwardly opening socket and with the socket projecting rearwardly from the front wall, the opening of the socket extending through the front wall the socket being transversely apertured, a hold-down stud for the necktie that is provided with an apertured shank portion that extends through the aperture of the necktie to have seating engagement within the socket, the apertures of the socket and the shank being in axial alignment when the stud is fully engaged in a hold-down position and an adjustable

locking pin carried by the rear side of the front wall for shiftable engagement through the socket and the shank.

2. In combination, an apertured necktie and a necktie holding clip formed of a single strip of metal bent upon itself to provide a non-slip and flexible clipping tongue and a front wall, a socket-forming housing carried upon the rear side of the front wall and with the socket opening through the front wall, the housing being transversely apertured, a headed stud having an apertured shank that extends through the aperture of the necktie for seating engagement within the socket, the shank when in fully seated engagement having its aperture in axial alignment with the aperture of the housing, a tubular internally threaded sleeve carried by the rear side of the front wall, a pin threadedly engaged with the sleeve, the pin being coaxial to the apertures of the housing and the shank when the latter is fully seated in the socket and a finger engaging head carried by the pin whereby the pin may be projected through the housing and the shank to retain the stud against displacement and in overlying hold-down relation to the necktie.
